PIPE STILL

D. Ronald Johnson, Ponca City, Okla., assignor
to Continental Oil Company, Ponca City, Okla.,
a corporation of Delaware

Application February 17, 1932, Serial No. 593,494

4 Claims. (Cl. 196—110)

My invention relates to a pipe still and more particularly to a pipe still for use in the processing and pyrolytic treatment of petroleum hydrocarbons.

5 In stills of this character, it is customary to have a convection bank protected from the radiant heat generated in the furnace by a bridge wall and a bank of tubes designed to utilize the radiant heat generated within the combustion 10 space. If the convection bank is subjected to a high temperature of radiant heat, the violent heating of the oil in this bank results in its decomposition and the deposition of carbon. This is particularly true of the upper tubes in the con- 15 vention bank. It has been found that a temperature of 1400° F. should not be exceeded in the entrant gases into the convection bank.

In order to prevent the critical temperature from being exceeded, a reduction of the furnace 20 temperature by the use of an excess of air is sometimes resorted to. It is obvious that this inefficient method results in a considerable loss of heat. In the United States Letters Patent to Primrose, 1,568,182, a method is shown of ob- 25 viating the difficulty by the use of a heat absorbing means above the convection bank.

One object of my invention is to provide a tube still construction which will preclude the over-heating of the oil in the tubes of the convection 30 bank and thus eliminate the necessity for the use of an excess of air or the employment of the absorbing means.

Another object of my invention is to provide a novel method of insuring the prevention of 35 overheating in the convection bank by means of indirect heat exchange to temper the gases entering the convection bank.

Other objects of my invention will appear from the following specification.

40 The figure shows a diagrammatic sectional view of a pipe still construction embodying one mode of carrying out my invention.

In general, my invention contemplates the 45 provision of a plurality of screen tubes inter- posed in the space between the top of the bridge wall and the top of the furnace to form a screen or grid through which the convection gases must pass before entering the convection bank. This 50 screen will shield the refractory material above the convection bank from the direct radiant heat and thus prevent this section of the furnace from reflecting radiant heat onto the top of the convection bank. The oil to be processed may be 55 introduced through the screen tube bank or other

material to be heated may be passed through the screen tube bank.

The number of rows of screen tubes is limited only by the draught conditions and the temper- 5 atures desired in the convection section. It is obvious that if the screen tube bank be made too large, the hot convection gases will be reduced too much in temperature.

Inasmuch as the screen tube bank will occupy 10 a position of high temperature, I propose to make the screen tubes of material which will stand somewhat higher temperature requirements than those existing in the other tubes of the still.

More particularly referring now to the draw- 15 ing, which forms part of the instant specifica- tion and which is to be read in conjunction therewith; the furnace walls 1 may be of any suit- able construction having air inlet openings 2 and burners 3. The interior of the furnace is divided by a bridge wall 4 which defines a com- 20 bustion space 5 in which is mounted a radiant heat tube bank composed of tubes 6 disposed around the sides and top of the combustion space and designed to receive the radiant heat gen- 25 erated within the combustion space 5. The hot gases of combustion pass over the top of the bridge wall 4 and downwardly on the other side thereof through the convection tube bank 7 com- 30 posed of convection tubes 8 and out through the flue connection 9. Between the top of the fur- 35 nace casing and the bridge wall 4, I position a bank of tubes 10 which I designate the screen tube bank. As pointed out above, this bank may be composed of a plurality of rows of tubes 11.

The hot gases of combustion will be tempered 35 by indirect heat exchange with the material pass- ing through the screen tube bank 10. At the same time the screen tube bank 10 will intercept the radiant heat generated in combustion space 5 and prevent it from striking the top of fur- 40 nace casing above the convection tube bank 7. It will follow, therefore, that the danger of the overheating of the upper tubes in the convection tube bank 7 will be eliminated.

Oil to be processed is introduced through pipe 45 12, through valve 13 and passes through screen tube bank 10. Inasmuch as the incoming oil is comparatively cold there will be little danger of this oil forming carbon deposits. The cold oil also will maintain the tube wall temperatures of 50 the screen tube bank within safe limits and thus avoid excessive stress and strain in the tubes. After the oil being charged leaves the screen tube bank, it may be passed through the remainder of the pipe still in any desired manner. For ex- 55

ample, it may leave the screen tube bank 10 through pipe 14 and pass through valve 15 into pipe 16, it being understood that valves 17 and 18 are closed. From pipe 16, the oil may pass 5 through the lower convection bank and out through tube 19 through portion 20 of the radiation tube bank through cross connection 21, through the remainder of the radiation tube bank, through line 22, through the upper portion 10 of the convection tube bank and out through line 23.

If desired, the screen tubes may be used for 15 heating any other product that may be desired. For example, the screen tubes may be used as a separate coil for reforming gasoline or other light hydrocarbon material at pressures ranging from 400 to 1500 pounds per square inch and at 20 temperatures of 750° to 1250° F. Even though partial cracking is obtained in the screen tubes under this condition, a high velocity of flow may be used to prevent deposition of carbonaceous 25 material and injury to the screen tubes due to high temperatures. When the screen tube bank is being used in this manner, valve 15 will be closed 25 and valve 17 will be opened and the oil to be processed in the pipe still will enter through valve 18 and pass directly into line 16 as will be obvious from the drawing.

Thus it is seen that I have accomplished the 30 objects of my invention. I have provided a construction which will prevent the overheating of the upper tubes in the convection bank. I have provided means for controlling the temperature of the convection gases entering the convection bank. I have provided a pipe still which will 35 prevent the overheating of the tubes in the convection bank and have provided a design which will enable the tempering means to be used as a separate heating system for special stocks. It is to be understood, of course, that water may be 40 passed through the screen tube bank for conversion into steam. Likewise the screen tube bank may be used as a steam superheater. While the screen tube bank is serving its other useful purposes, it will at all times act as a grid or a screen 45 to prevent the impinging and subsequent reflection of the radiant heat.

It will be understood that certain features and 50 sub-combinations are of utility and may be employed without reference to other features and sub-combinations. This is contemplated by and is within the scope of my claims. It is further 55 obvious that various changes may be made in details within the scope of my claims without departing from the spirit of my invention. It is, therefore, to be understood that my invention is not to be limited to the specific details shown and described.

Having thus described my invention, what I 60 claim is:

1. A tube still comprising in combination a setting divided into two sections by a bridge wall

and partition tube bank in substantially the same plane as the bridge wall, means for burning fuel in one of said sections, means communicating with the other of said sections for withdrawing gases of combustion from said setting, a tube bank disposed in said fuel burning section adapted to be heated mainly by radiant heat, a tube bank disposed in the other of said sections adapted to be heated mainly by convection heat, means providing communication between said tube banks whereby hydrocarbon oil to be treated may be passed through said convection heated bank and said radiant heated bank in series, and means for passing an extraneous cool medium through said partition tube bank.

2. A method of heating hydrocarbon oils including the steps of generating gases of combustion in a combustion zone and passing the products of combustion through a gas passage, heating a hydrocarbon oil first by heat exchange with 20 the hot products of combustion in the gas passage, then mainly by radiant heat in said combustion zone, and then mainly by convection heat in the gas passage, and reducing the temperature of the gases leaving the combustion zone 25 and entering the gas passage by heat exchange with an extraneous cool medium, in a zone exposed to direct radiant heat from the combustion chamber.

3. A tube still comprising in combination a 30 setting formed with a combustion space and a gas passage, a tube bank adapted to be heated mainly by convection heat disposed in said gas passage, a tube bank adapted to be heated mainly by radiant heat disposed in said combustion 35 space, means connecting said tube banks in series for the passage of oil therethrough, a separate tube bank exposed to direct radiant heat from the combustion chamber, interposed between said combustion space and said gas passage, and means for passing an extraneous cool medium 40 through said separate tube bank for reducing the temperature of the hot gases of combustion leaving said combustion space and entering said gas passage.

4. A tube still comprising in combination a setting formed with a combustion space and a gas passage, a tube bank adapted to be heated mainly by convection heat disposed in said gas passage, a tube bank adapted to be heated mainly by radiant heat disposed in said combustion space, means connecting said tube banks in series for 50 passage of oil therethrough, a separate heat absorbing element exposed to direct radiant heat from the combustion chamber, interposed between said combustion space and said gas passage, and means for passing an extraneous cool medium 55 through said separate heat absorbing element for reducing the temperature of the hot gases of combustion leaving said combustion space and entering said gas passage.

D. RONALD JOHNSON.
